W. L. REARDON

SPARK PLUG

Original Filed July 3, 1922

INVENTOR

W. L. REARDON,

BY

L. M. THURSTON

ATTORNEY.

UNITED STATES PATENT OFFICE.

WILLIAM L. REARDON, OF PEORIA, ILLINOIS.

SPARK PLUG.

Application filed July 3, 1922, Serial No. 572,480. Renewed April 30, 1926.

This invention relates to improvements in spark plugs.

Said invention pertains more particularly to a spark plug of the double end variety or that having terminals at each of its ends whereby said plug may be reversed in position in the cylinder head.

The objects of the invention are to provide a spark plug of the double-end type that, by reason of the peculiar manner in which it is constructed and assembled, will be free of compression leaks around the parts or between them; there will be no danger of internal short circuits; that an intensifying of the spark at the terminals within the combustion chamber will result from the employment of an external spark gap; that the condition of the plug at the inner firing terminals may be determined by observing the form and condition of the spark at the outer terminals; and that when the said inner terminals become fouled as indicated by the appearance of the spark at said outer terminals, the plug may be reversed in position thus presenting clean terminals to the firing charge.

To the end that the invention may be thoroughly understood I have provided the accompanying drawing forming part hereof wherein

Figure 1 is a side elevation of the plug of my invention.

Figure 2 is a similar view showing one half of the plug in longitudinal section.

Figure 3 is a plan of the plug as viewed at one of its ends, and

Figure 4 is a detail, in section, of part of one of the shell portions of the plug.

The plug includes two metal shell-portions 1, 2 each having a base 3, one of which is shown at the left of Figure 2, each said portion being externally threaded, as in common practice, to engage the threads of the cylinder head, not shown, and the inner end of each of the shell-portions is reduced to a comparatively thin edge as shown at 4 in Figure 4, the purpose of which will now appear.

The said bore 3 is enlarged as shown at 5 and receives into it a porcelain insulator 6 of a form that will fit into the said enlarged bore 5 in a fairly snug manner and rest upon a shoulder 7 of the shell, there being a gasket 8 between said shoulder and the insulator forming a tight closure. The said insulator is reduced in diameter at its

inner end leaving a shoulder 9 to receive a gasket 10, the edge 4 of the shell being swedged inwardly upon it making an absolutely leak tight joint, a filling of cement 60 being interposed between the insulator 6 and the shell, if desired, before resorting to the swedging process.

The complete plug is made up of two companion portions of the construction just described, it being observed in Figure 2 that the insulators 6 of each abut one against the other spacing the shells apart the distance required to prevent a spark jumping from one to the other.

Preferably, as in common practice, the outer ends of the insulators are reduced considerably in diameter and extend toward the outer ends of the shells. Furthermore, the insulators are provided with bores 6' centrally and longitudinally to receive a double-end terminal rod, or electrode, whose extremities are designated at 11. Said rod midway its length has an enlargement 12 and is roughed preferably by providing 80 screw threads 13, while midway of the enlargement is a flange 14.

The bores 6' of the insulators receive the enlargements 12 and are preferably threaded, and the abutting ends are recessed at 15 85 to receive into them the said flange 14 of the said electrode 11.

In assembling the plug the shell portions 1, 2 are completed as described whereupon cement of a kind that will become vitrified 90 under a baking heat is placed in the enlarged bores of the insulators, the terminal rod or electrode being then inserted and screwed into the plastic cement, such cement by the entrance of the rod, being also carried down into the smaller bore that receives the outer end of the electrode. Having thus completed one half of the plug, an insulating sleeve 16 is placed over the insulator 6 of that half, the other half having been treated to the cement is screwed upon the enlargement 12 and finally forced against the said sleeve 16, the cement filling any and all spaces around the flange 14. When complete, the plug is placed in an 105 oven to vitrify the cement filling, after which the plug is ready for use.

The sleeve 16 serves two purposes. It aids in preventing the high tension current jumping between the shells 2, and it also braces the structure by being clamped between the said shells so that lateral blows

21
will not be likely to snap the porcelain insulators 6, disrupting the plug.

As a convenient contact portion for the cable leading to the ignition I provide a 5 spring clip 17 to snap around the threaded portion of the plug as a very effective and convenient connection easily attached and detached.

The threads 13 upon the enlargement 12 10 and the threads in the bore 6' of the insulators 6 provide roughened surfaces to better retain the parts in intimate and permanent engagement, and while other roughing methods may be employed the described 15 threads are easily formed and they assist in assembling the parts on which they are formed.

In the structure as I provide it, the electrode 11, 12 is wholly insulated and widely 20 spaced from the shell portions 1, 2 so that "shorting" cannot occur, and since the said shell portions are snugly closed upon the insulators there can be no gas leaks. Furthermore, the wide spacing of the shell portions through the sleeve 16 and the extended insulator portion abutting within 25 said sleeve, the high tension current cannot jump from one shell to the other, this being of the utmost importance.

30 Should the plug become fouled it may be reversed in position and the fouled end will automatically clean itself of accumulated oil since the outer end, or that outside the combustion chamber, is always a spark gap 35 in the open air. Furthermore, the condition of the plug at its inner or firing end is reflected in the outer terminals in that when said inner end becomes fouled a yellow spark will appear at the outer end, a 40 clean plug showing at the said outer terminal the usual blue flame. Again, the condition of the ignition system is always readily determined since a failure of a spark to appear is easily noted and the trouble can 45 be directly traced to its source.

As constructed, my plug is made in separate portions, as explained, so that the sealing of the passages by means of the gaskets 8 and 10 by swedging of the portion 4 can 50 be properly done without cracking or breaking the porcelain as would occur where a one piece porcelain is employed and therefore a thoroughly reliable article is the result.

Again, in practice porcelain or clay product 55 insulators must be baked in an intense heat for several days, the intensity of the heat being such that metals would become fused. It is therefore necessary to bake such porcelains separately and then insert 60 in the bore provided for it the electrode 11 as the only method that can be used as now known.

In other words, in order that the plug can 65 be made commercially or at all, in fact, the porcelain must be constructed and baked

separately; then assembly of the separate parts is wholly practicable and a plug of commercial value is assured.

I claim:

1. A spark plug of the double ignition 70 type including in its construction a pair of separate insulating cores each having in one end a recess for receiving part of an electrode and having in its other end a bore communicating with its said recess, the bore 75 and recess creating an opening entirely through said core, the recessed ends of said cores abutting with the axes of the recesses and bores in alignment, a single electrode lying within the cores and extending through 80 the cores and beyond the outer ends of the assembled cores, said electrode having an enlargement of a considerable length at the middle of its length to occupy the recess in each of the cores, a cement filling introduced 85 between the electrode enlargement and the walls of the recesses serving with the said electrode to secure it and the cores in connected relation, a separate shell electrode enclosing each core and spaced from one 90 another, and a sleeve of nonconducting material interposed between, abutting upon, and spacing the last named electrodes and serving to brace and protect the assembled cores from lateral breaking strains. 95

2. A spark plug of the double ignition type including in its construction a pair of separate insulating cores each having in a portion thereof a recess for receiving part of an electrode, and having in the remaining portion a bore communicating with its said recess, the bore and recess creating an opening entirely through the core, there being a second larger recess in the end surface of each core communicating with the first recess therein, said cores abutting at their recessed ends with the axes of the recesses in alignment, a single electrode lying within the cores, extending through the 100 bores and beyond the outer ends of the assembled cores and having an enlargement of considerable length at the middle of its length lying within both the first named recesses, said electrode having a further enlargement at its middle greater in diameter 105 than the first and lying within the second named recess and between the assembled cores, a cement filling introduced between the electrode enlargement and the walls of the recesses serving with the said electrode to secure the latter and the cores in connected relation, a separate shell electrode enclosing each core, spaced from one another, and a sleeve of nonconducting material interposed between, abutting upon, and spacing the last named electrodes and serving to brace 110 and protect the assembled cores from lateral breaking strains. 115
